UNITED STATES PATENT OFFICE.

LESTER D. CROSBY AND JOHN F. HEALY, OF WINDSOR, CONNECTICUT.

TRICK TOY.

SPECIFICATION forming part of Letters Patent No. 587,795, dated August 10, 1897.

Application filed November 7, 1896. Serial No. 611,342. (No model.)

To all whom it may concern:

Be it known that we, LESTER D. CROSBY and JOHN F. HEALY, citizens of the United States of America, residing at Windsor, in the county 5 of Hartford and State of Connecticut, have invented a certain new and useful Improvement in Toilet Devices, of which the following is a description, reference being had to the accompanying drawings, wherein—

10 Figure 1 is a view in central vertical section. Fig. 2 is an exterior view.

The object of the improvement is the production of a device useful for such a purpose as the application of the odor of menthol to 15 the face or forehead of a person or to the distribution of toilet powder thereon. Said device is made in the form of an imitation whistle, though not productive of sound, and may be used as a trick toy.

20 In the accompanying drawings the letter *a* denotes a hollow casing which forms the main body of the device and contains or comprises within it the chamber *b*.

The letter *c* denotes what may be termed 25 the "mouth-plug." It is traversed by the air-conduit *d*, which leads to the rearward part of the chamber.

The letter *e* denotes a removable stopper by means of which the chamber contents may 30 be introduced within the chamber *b*.

The letter *f* denotes the chamber-vent, it being an orifice in the wall of the chamber formed and adapted in its shape to direct the chamber contents, when they are expelled from the chamber, toward what may be termed 35 the "mouth end" of the device.

In the use of this device the menthol, powder, or other chamber contents are placed within the chamber *b*, the user puts what may be termed the "mouth end" of the device 40 in his mouth, and by blowing thereon he forces his breath through the air-conduit into the rearward part of the chamber *b*, expelling the chamber contents through the chamber-vent to and upon that portion of the face and 45 forehead to which it may be directed.

We claim as our improvement—

An imitation whistle, consisting of the hollow casing *a*, having chamber *b*, mouth-plug *c* provided with conduit *d* leading diagonally 50 downward and opening into the said chamber *b* at the rear, air-vent *f*, at the upper rear portion of chamber *b*, and removable stopper *e*, all substantially as specified.

LESTER D. CROSBY.
JOHN F. HEALY.
